UNITED STATES PATENT OFFICE.

BRODIE J. RICHARDSON AND CLAIRE S. BARBER, OF WATERBURY, CONNECTICUT.

LOCK-LATCH FOR HANDBAGS.

1,392,967.

Specification of Letters Patent. Patented Oct. 11, 1921.

Application filed March 15, 1920. Serial No. 366,001.

To all whom it may concern:

Be it known that we, BRODIE J. RICHARDSON and CLAIRE S. BARBER, citizens of the United States, and residents, respectively, of Waterbury, in the county of New Haven and State of Connecticut, have jointly invented certain new and useful Improvements in Lock-Latches for Handbags, which improvements are fully set forth in the following specification.

This invention relates to improvements in key-operable devices of that class available conjunctively with a suitable tenoned hasp for locking together the customary hinged frame-sections of a hand-bag or the like, such devices being well-designated lock-latches for hand-bags.

The object of this invention is to provide a lock-latch of the character above indicated, which shall be simple and comparatively inexpensive as regards its construction; which shall embody certain novel features of construction whereby is facilitated the operation of assembling the various parts thereof, and whereby access to the tumbler of the device shall be rendered markedly involved, save through the medium of a key specially provided therefor; and which shall possess certain well-defined advantages over prior analogous constructions.

The invention consists in certain novel combinations, details and parts whereby the attainment of the foregoing object is rendered practicable, and which will be herein-after more specifically referred to and set forth in the claims hereto appended.

The invention is clearly illustrated in the accompanying drawing, wherein:

Figure 1 is a top plan view of a lock-latch embodying our said improvements.

Fig. 2 is a view of same partly in rear elevation and partly in section.

Fig. 3 is a view similar to Fig. 1, the top plate being removed and the medial portion of the operating-bolt being broken away.

Fig. 4 is an end elevation of the device, the near end wall and a portion of the front wall of the housing being broken away.

Fig. 5 is a detail view partly in elevation and partly in section, showing the application of a key to the key-receiving arbor of our improved lock-latch.

Fig. 6 is an enlarged detail plan view of certain minor parts of the device, detached, the same showing a modification of the key-

way formed in the key-receiving arbor aforesaid.

Fig. 7 is an end elevation of the operating bolt, detached.

In carrying out our present invention, reference being had to the accompanying drawing, wherein similar reference-numerals denote like parts throughout the several views, we provide a general housing formed, by preference, from a blank of metal in sheet-form, and consisting of a base 2, top-plate 2', front wall 3 and opposite end-walls 4, 4'.

A centering-spindle 3' is riveted at its lower end to the base 2, and at such a point therealong as to rise fixedly therefrom centrally within the housing aforesaid, said centering-spindle being fitted with an annular base-seat 5 for the reception of a suitable base 5', and said base, while surrounding said centering-spindle detachedly, is limited in its movement downwardly therealong through the medium of the base-seat aforesaid.

The centering-spindle 3' freely pierces, primarily an evener 5" and thereafter an operating-bolt 5'", a controlling spring 6, preferably spiral in form, normally encircling said centering-spindle, between said evener and the base aforesaid, and whose tendency is to indirectly exert an elastic force on the operating-bolt aforesaid, to hold the same at all times duly protracted, all substantially as set forth in our co-pending application, Serial No. 345,067, and to the general subject matter of which our present improvements more particularly relate.

In this instance the upper portion of the centering-spindle is preferably reduced in diameter relatively to the lower portion thereof; and, in addition to piercing said evener and said operating-bolt, the same freely pierces the hub 6' of the segmental tumbler 7, said tumbler-hub being positioned intermediate the medial section of the operating-bolt aforesaid and the evener aforesaid and serving incidentally to duly space apart these parts.

The tumbler-hub 6' has formed thereon a diametrically reduced, depending boss 7', which extends freely downward through and suitably beyond the evener 5", and bears therein, there being further formed on said tumbler-hub at its upper end, a

diametrically reduced key-receiving arbor 8, which projects upwardly through and somewhat beyond the medial section of the operating-bolt 5''' thereabove, and bears 5 therein, whereby are insured a more positive and dependable rotative action on the part of the tumbler aforesaid, and a more positive and dependable general action on the part of the evener aforesaid, the latter under the tendency of the controlling spring 6 bearing upwardly thereon.

10 The tumbler-hub 6' is fitted with an appropriate bore 8', into which projects upwardly, to a suitable extent, the reduced 15 portion of the centering-spindle aforesaid, and downwardly along which reduced portion of the centering-spindle, and against the tendency of the spring 6, may be collectively depressed, as under finger-pressure suitably applied thereto, said operating bolt, said evener, and said tumbler operating therebetween, such downward movement of said collective parts being limited by the boss 7' coming in contact 20 with the annular shoulder 9, which serves as a stop therefor and which results from the variation in diameter of said centering-spindle and its said reduced extension, as will be readily understood.

25 30 Hence, through the medium of the tumbler-hub aforesaid conjunctively with said evener, the distending tendency of the controlling spring 6 is transmitted indirectly to said operating-bolt to elastically hold the same at all times duly protracted, with its medial section in contact with and underlying the top-plate 2', the tumbler 7, including its hub 6', and the key-receiving arbor rising from said tumbler-hub and, 35 fitted with a suitable key-way 9' being rotatable all as a unit, accordingly, on and relatively to said centering-spindle.

More specifically, and as defined in our 40 said co-pending application, the medial section of the operating-bolt 5''' is merged into a downturned segment 10, which is merged, in turn, into a depressed, horizontal segment 10', the latter being merged, in turn, into a forwardly projecting terminal 10'', fitted with an upstanding catch 11, said catch having a vertical rear edge and an advance edge curved upwardly and rearwardly, substantially as shown, and said segments and catch-affording terminal 50 55 being, respectively, correspondingly formed and duplicated at the opposite end of the medial section of the operating-bolt 5''', when deemed needful or desirable.

The front wall of the housing aforesaid 60 has a fragment thereof drawn inwardly therefrom for the formation of a horizontal ledge 11', whose function will be made apparent hereinafter, said front wall being further provided with a suitable opening 65 11'' by way of which the tenon, as 12, of a

suitable hasp, as 12', may be projected into the interior of the housing aforesaid, and which operation necessitates the engagement by said tenon of the upwardly and rearwardly curved edge of the catch, as 11, provided for co-operation therewith, with the result that said catch is momentarily depressed and, under continued movement inwardly of the tenon, permitted to snap back into a locking engagement with said tenon; 70 75 which locking engagement may again be broken, as through depression of the operating-bolt 5''', fitted with said catch, all as in common practice and as will be readily understood, the opening and hasp tenon 11'' 80 being employed in duplicate when deemed needful or desirable, and as indicated in the drawing.

Depression of the operating bolt 5''' is facilitated through the medium of a hollow 85 finger-piece 13, the same being firmly mounted on the operating-bolt, and having an opening 13' formed centrally in the crown thereof.

It is contemplated and preferred that the 90 mounting of the finger-piece 13 shall be effected by means of opposite lugs 14, 14', so formed thereon as to permit of their being projected downwardly through openings 15, 15', formed oppositely through the 95 operating-bolt aforesaid, the same being thereafter turned, each oppositely away from the other and into snug contact with such operating-bolt at the under face thereof, due clearance to this end being provided in the opposite, downturned segments 10, as at the points 16, 16', respectively, thereof.

17 denotes a key-way finder, arranged vertically and centrally within the depressible finger-piece 13 and compressible as a unit therewith, the same approximating the form of a barrel, by preference. Said key-way finder rotatively encircles at its lower end 105 the upper end-portion of the key-receiving 110 arbor 8 and is fitted at its top with an upwardly drawn, diametrically reduced crown 17', which projects into the opening 13', bears rotatively therein, and has formed therein an exposed key-opening 18, which 115 key-opening is adapted to be brought, under due rotative manipulation of said key-way finder, into diametric registry with a suitable co-acting notch 18', formed in the crown of the finger-piece 13 at the margin thereof 120 surrounding the opening 13', and preferably into like registry with an additional similar notch 18'', diametrically opposite to the notch 18'.

In this instance the finder 17, taking the 125 form of a barrel, has an annular flange 19 inturned at its lower end, which flange more directly encircles the upper end of the arbor 8, and includes a key-recess 19', arranged at 130 all times in diametric registry with the key-

opening 13' thereabove, and preferably includes a similar key-recess 19'', arranged oppositely to the key-recess 19' and in like registry with the said key-opening thereabove.

The arbor 8 projects upwardly through and measurably beyond the operating-bolt 5''' by way of a suitable opening 20 formed medially therein, and which opening includes a minor key-clearance 20', arranged at all times in diametric registry with the notch 18' thereabove, and preferably includes a similar key-clearance 20'', arranged oppositely to the key-clearance 20', and in corresponding registry with the notch 18'' thereabove, when employed.

The tumbler 7 occupies at all times a horizontal plane slightly elevated with respect to the ledge 11'. Hence, when said tumbler shall have been so rotated at any time on the centering-spindle 3', say, to the position indicated in full lines in Fig. 3, as to cause a marginal segment thereof to overlie said ledge, the operating-bolt 5''' will thereby be securely locked against retraction; while retraction of said operating-bolt will be permitted whenever the tumbler 7 shall have been so rotated at any time on the centering-spindle 3', say, to the position indicated in dotted lines in Fig. 3, as to withdraw the margin of said tumbler, in its entirety, from its said position overlying said ledge.

The operation of rotating the tumbler 7 for the purposes above defined, may be conveniently accomplished only through the medium of a special, relatively flat, suitably notched key, as 21, whose application to the purpose is intentionally rendered quite involved, and may be stated as follows:

Assuming that the key-way finder 17 shall have been so rotatively shifted as to bring its key-opening 18 out of registry with the notch or notches aforesaid provided for coöperation therewith, said key-opening and said notch or notches may be readily brought into registry by duly manipulating, rotatively, said key-way finder, as through the medium of the key 21, whose advance end, for this purpose, is measurably inserted into the key-opening 18; and upon the latter being thus brought into registry with said notch or notches, said key may be caused to now move, advance-end foremost, downwardly with respect to the finder 17, in the direction of and into the key-way 9' thereunder. Whereupon, said key-way being now in diametric registry with the key-recess, or key-recesses, aforesaid provided for coöperation therewith, said key may be caused to

still further move, advance-end foremost, downwardly through and suitably beyond the medial section of the operating-bolt 5''', the key-clearance or key-clearances aforesaid, being now in diametric registry with the key-way aforesaid, formed in arbor 8;

whereupon,—the edge-recess 21', including a like edge-recess 21'', when found needful, being now positioned to clear the adjacent margin of the material of the crown of the finger-piece 13, and the similar edge-recess, 22, including a like edge-recess 22', when found needful, being now positioned to clear the adjacent margin of the material of the medial section of the operating-bolt 5''', more or less of said edge-recesses as may be found desirable in practice being contemplated for the key aforesaid,—rotation of said key may now be effected, and through the medium whereof tumbler 7 may be correspondingly rotated, and in a manner and to an extent to cause some segment of the margin thereof to overlie the ledge 11', whereby the operating-bolt 5''' becomes locked, through the medium of said ledge, against retraction, or to liberate said operating bolt for retraction, all as will be clearly understood.

The evener 5'' serves both as a yielding retarder of the tumbler 7 when rotated, and as a medium whereby the operating-bolt 5''', including said tumbler, is essentially constrained to move more evenly upwardly and downwardly along the centering-spindle 3', the depending portion or portions of said operating-bolt being thereby serviceably held against any undue swinging action, as on a center of movement defined by the medial, horizontal section thereof.

To the foregoing ends the evener 5'' has an end-detent 23, which at all times occupies an open recess 23', with which the downturned segment 10 of the operating-bolt aforesaid is provided, said recess being ample to afford measurable clearance immediately beneath said detent, to permit a measurable, downward tilting action on the part of said evener, together with the detent carried thereby, against the tendency of the controlling spring 6, and independently of the operating-bolt 5'''; which action on the part of said evener takes place whenever the tumbler 7 shall be duly rotated on the centering-spindle 3'', and by reason of the same engaging, depressing and overriding the small boss 23'', afforded by said evener, and whose opposition to being so depressed insures the retardatory effect hereinbefore alluded to on said tumbler by said evener.

When deemed advisable, the evener 5'' may be provided with a suitable upstanding stop 24, which projects into the plane of movement of the tumbler 7 and serves to limit the extent of rotative action thereof in either direction of the centering-spindle 3'.

It will be noted that the base 5' is materially enlarged relatively to the diameter of the spring 6, which facilitates the clamping of said base against the bottom plate 130

of the housing of our improved device, and whereby riveting the lower, reduced end portion of the centering-spindle 3' to said bottom plate is facilitated.

5. The operation of our improved lock-latch should be apparent from the foregoing description thereof, the same, in practice being mounted on one hinged frame-section of a hand-bag, or the like, for coöperation with 10 a suitable, tenoned hasp, mounted on the opposite hinged frame-section of such handbag, or the like, as is usual in the art; and to which end, the housing of our improved lock-latch is, in this instance, provided with 15 suitable lateral, opposite extensions fitted, respectively, with rivet-openings 24', 24".

It will be seen that our improved latch is well adapted for the purposes for which it is intended, and further that the same 20 may be modified to a considerable extent, particularly as regards the specific form of the key-opening 18 in correspondence with the key-way thereunder, a modification whereof is shown in Fig. 6, together with 25 various minor details of the general construction, without materially departing from the spirit and principle of our invention, as expressed in and coming within the scope of the claims hereto appended, the 30 flat key made use of being longitudinally crimped, or otherwise modified in cross-section to conform to any modification in form of the key-opening and key-way aforementioned.

35 Having thus described our invention, we claim:

1. A lock-latch of the class herein described comprising a housing having an up-standing, shouldered centering-spindle fixed 40 therein; depressible latch-mechanism centered by and operating on said centering-spindle, said latch-mechanism including an operating-bolt, an evener, and a spacing me-

dium, the latter positioned between said operating-bolt and said evener, and fitted with 45 a boss extending downwardly through and beyond the evener, and adapted to engage the shoulder afforded by said centering-spindle for limiting the extent of depression of said latch-mechanism.

2. A lock-latch of the class herein described comprising a housing having an up-standing centering-spindle fixed therein; depressible latch-mechanism centered by and operating on said centering-spindle, said 55 latch-mechanism including an operating-bolt engageable with the tenon of a hasp and having a medial opening including a minor key-clearance; and a tumbler, the latter affording a reduced key-receiving arbor projecting upwardly freely through said operating-bolt, by way of the medial opening therein, and fitted at its top with a key-way adapted to be brought into registry with said key-clearance, and whose bottom is 60 beneath said operating-bolt; and means co-acting with the tumbler aforesaid whereby 65 said latch-mechanism is locked against depression and liberated for depression under varying rotative adjustments of said 70 tumbler.

3. A lock-latch of the class herein described comprising a housing having a spring-controlled operating-bolt therein; a hollow finger-piece fixed on said operating-bolt and rising therefrom through the top-plate of said housing, said finger-piece having an opening formed medially in the crown thereof and including a notch; and a 75 key-way finder, the latter rotatable within 80 said finger-piece and having an exposed key-opening at its top, said key-opening adapted to be brought into and out of diametric registry with the notch aforesaid.

BRODIE J. RICHARDSON.
CLAIRE S. BARBER.
